UNITED STATES PATENT OFFICE

2,545,824

STIRRER

Richard A. McDonald, Easton, Pa., assignor to
 General Aniline & Film Corporation, New
 York, N. Y., a corporation of Delaware

Application November 13, 1948, Serial No. 59,797

3 Claims. (Cl. 259—96)

1

This invention relates to a stirrer of the centrifugal pump type adapted to be positioned in and operated in relatively shallow tanks such as used in the treatment of photographic film and paper.

In photographic work it is oftentimes desirable to have efficient agitation of thin layers of liquid without causing excessive turbulence or frothing, particularly so that aerial oxidation will be held to a minimum. The developing, fixing and washing of photographs is usually done in relatively shallow trays or tanks and it is desirable to stir the liquid in contact with the photographs so that a fresh layer of solution or water replaces the used solutions adjacent to the face of the photograph.

An object of the invention is to provide a stirrer of this nature having a novel discharge orifice.

A further object of this invention is to provide a stirrer with the intake and exhaust ports adapted for stirring a thin layer of liquid.

These and other objects are attained by the means described herein, a preferable form of which is illustrated in the drawings. In general the invention relates to a rotary stirrer comprising an enclosed chamber, rotary means within said chamber for establishing centrifugal flow, an intake opening in said chamber near the central axis thereof and a discharge opening at the periphery of said chamber comprising an elongated thin slit.

In the drawings:

Fig. 1 is a side elevational view partly in section of the stirrer of this invention associated with a suitable operating motor.

Fig. 2 is a bottom view of the stirring device as indicated by the lines 2—2 of Fig. 1 and

Fig. 3 is an elevational view of the various parts of the stirrer shown in Fig. 1 unassembled.

Referring to the drawings, there is shown a motor 10 on motor stand 11 connected to the stirrer blades 12 by means of shaft 13. Supports 14 connect the motor stand with the stirrer chamber 15 by means of a collar 16 adapted to be held immovably on bushing 17 by means of a set screw 18. The blades 12 are held in a suspended position in chamber 15 by means of the shaft bushing 20 held to the shaft by set screw 21 and in operation frictionally engaging the top of bushing 17. Flat disc-like pump chamber 15 is formed of two plates 23 and 24. The plate 23 has a hole in the center sufficient to admit the shaft 13 and plate 24 is provided with an enlarged central aperture 25 through which

2

the liquid enters the stirrer and a collar 26 of sufficient thickness to allow the plates 12 to rotate freely between plates 23 and 24. The collar is discontinuous at the top edge thereof forming an elongated semi-circular slit 28 in the chamber when plate 23 is in place on top of plate 24. The plates are held together by known means as by set screws 30.

In operation, the stirrer is placed preferably at one corner of the shallow pan containing the liquid to be stirred and is elevated slightly off at the bottom of the pan as by means of a stand, not shown, adopted to hold the entire device at an adjustable distance from the bottom of the pan, or by placing small legs under the stirrer chamber. Upon entering the chamber the liquid is forced by centrifugal action out through the slit in the chamber so that a very thin fan shaped stream of liquid comes from the stirrer.

It will be obvious that the power may be transmitted to the blades by means other than the electric motor, that the bearing surfaces may contain ball bearings or the like, etc. It will further be obvious that the blades may be of any one number of types such as cupped or propeller-like but that the flat blade illustrated is particularly desirable. Alternatively also the liquid entrance port may be on the upper side of the pump chamber and the chamber may then rest on the bottom of a vessel.

Essentially, the stirrer is a centrifugal pump, but has several features which have not previously been found in such pumps. One of the new features of the stirring mechanism is the slit outlet which causes the liquid being pumped to be ejected in a sheet-like form rather than as a solid stream. Stirrers of this type may be made small enough to circulate a $\frac{1}{16}$ inch thick layer of liquid or even less. The slit may be substantially circular instead of $\frac{1}{8}$ semi-circular, as illustrated, and the stirrer may thus be placed in the middle of a tray and the liquid caused to flow in all directions, although it is an important advantage of the preferred form of the invention that it need not be placed in the middle of a vessel. The enclosed stirring blade renders it less hazardous for fragile equipment and photographic supplies. By placing a mesh over the opening at the bottom of the stirring devices, the stirrer can be operated in the presence of glass beads, clay plate chips, etc.

Besides photographic uses and the like, the stirrer may also be used for the preparation of oil-in-water or water-in-oil emulsions due to the high shearing force developed by the blades and

the rapid ejection of the thin sheet of liquid into the main body.

It may, of course, be used in vessels other than shallow pans and thus has general utility in laboratory use. Its enclosed blades are a safety factor.

Other alterations and modifications may be made within the scope of the following claims.

I claim:

1. A rotary stirrer adapted to emit a thin sheet of liquid within a shallow liquid body, comprising an enclosed disc-like chamber, a plurality of rotary blades within said chamber adapted to establish centrifugal flow, an inlet near the center of said chamber adapted to admit liquid flowing by gravity into said chamber, and a discharge opening at the periphery of said chamber comprising an elongated thin slit adapted to direct a thin sheet of liquid away from the central axis of said chamber.

2. A rotary stirrer adapted to emit a thin sheet of liquid within a shallow liquid body, comprising an enclosed disc-like chamber, a plurality of rotary blades within said chamber adapted to establish centrifugal flow, an inlet near the center of said chamber adapted to admit liquid flowing by gravity into said chamber, and a discharge opening at the periphery of said chamber comprising an elongated thin slit around substan-

tially the entire periphery of said chamber and adapted to direct a thin sheet of liquid away from the central axis of said chamber.

3. A rotary stirrer adapted to emit a thin sheet of liquid within a shallow liquid body, comprising an enclosed disc-like chamber, a plurality of rotary blades within said chamber adapted to establish centrifugal flow, an inlet near the center of said chamber adapted to admit liquid flowing by gravity into said chamber, and a discharge opening at the periphery of said chamber comprising an elongated thin slit in about one-third of the periphery of said chamber and adapted to direct a thin sheet of liquid away from the central axis of said chamber.
